UNITED STATES PATENT OFFICE.

EDWARD POSSON, OF CHICAGO, ILLINOIS.

CARRIER FOR DRAW-BARS.

1,284,140.

Specification of Letters Patent.

Patented Nov. 5, 1918.

Application filed September 16, 1915. Serial No. 50,970.

To all whom it may concern:

Be it known that I, EDWARD POSSON, a citizen of the United States, residing at Chicago, in the county of Cook and State of Illinois, have invented certain new and useful Improvements in Carriers for Draw-Bars, of which the following is a specification.

This invention relates to an improved carrier for the draw-bar of a railway car. The principal object of the invention is to provide an improved draw-bar carrier which is adapted to be attached to the framework of a car, and which supports the draw-bar in an improved and efficient manner. Another object is to provide a draw-bar carrier having a roller adapted to coact with and support the draw-bar. Still another object is to provide a carrier having supporting arms or brackets carried by the end sill or other parts of the car framework, and having detachably supported thereby a roller which is adapted to coact with the draw-bar. A further object relates to the combination of my improved draw-bar carrier with the usual dead block or reinforcing member carried by the end sill; and still a further object relates to the improved means for detachably mounting in the supporting brackets of the carrier the roller which coacts with the draw-bar.

These and other objects of the invention will be more particularly set out in the following specification, taken in connection with the accompanying drawings, in which one embodiment of the invention is illustrated.

In the drawings—

Figure 1 is an end elevation of a portion 40 of a railway car showing my improved draw-bar carrier;

Fig. 2 is a top plan view of a portion of the railway car showing a similar view of my improved carrier;

Fig. 3 is a longitudinal section through the end of a railway car showing a side elevation of the draw-bar carrier and the dead block carried by the end sill;

Fig. 4 is a sectional view taken on the line 50 4—4 of Fig. 2; and

Fig. 5 is a sectional view taken on the line 5—5 of Fig. 3.

In the drawings my improved draw-bar carrier is shown in assembled position on a

railway car, which comprises the end sill 10, 55 end wall 11, floor 12, and draw-bar 13. The lower central portion of the end sill is cut away to form an aperture 14, through which the draw-bar extends. The dead block 15 is secured to the end sill around the aperture 14, by means of the bolts 16, and serves to reinforce the end sill around said aperture. The dead block is constructed to fit closely the channel of the end sill 10, as clearly shown in Fig. 3; and it comprises the plates 65 15^a which are bolted to the end sill, the buffer plate 15^b which is located above the aperture 14, the vertically extending flanges 16^c on either side of the aperture 14, and the outwardly directed horizontal flanges 15^d 70 which project outwardly from the lower flange of the end sill. The outwardly extending flanges 15^d of the dead block are reinforced by ribs 15^e, and the plate 15^b is reinforced by ribs 15^f.

My improved draw-bar carrier comprises two oppositely disposed brackets 20, which in the construction here shown are secured to the horizontal flanges of the dead block by means of the bolts 21 and 22. Each of 80 the brackets 20 comprises two parallel downwardly extending flanges 20^a and 20^b, and two transversely arranged flanges 20^c. Between these flanges of each bracket there is formed a recess or pocket 23, which communicates with the bolt hole through which the bolt 22 extends. Each bracket also comprises an outwardly extending flange 20^d, which seats against the dead block and is engaged by the other securing bolt 21. The 85 parallel depending flanges 20^a and 20^b of each bracket are provided with alining apertures 24 and 25, which are adapted to receive and form bearings for the horizontally extending axle member 26, it being understood that this axle member engages the apertured flanges 20^a and 20^b of each of the oppositely disposed brackets 20. The flanges 20^c are grooved at 20^b to form continuations of the apertures 24 and 25, since 100 the axle member has a diameter greater than the width of the pocket 23. A cylindrical roller 27 is journaled upon the axle member 26 between the bracket members and is arranged to coact with the draw-bar 13 to support the same.

The outer flanges 20^c of the brackets are provided with inwardly and downwardly

inclined apertures 28, which align with cylindrical inclined sockets 29 formed in the inner flanges 20°. The apertures 28 and sockets 29 are adapted to receive the headless pins 30, which pins also engage alining apertures 31 formed in the axle member 26. The socket 29 in the innermost flange 20° of each bracket terminates in a shoulder 31, which coacts with the end of the corresponding pin 30 and supports the same in position. A smaller aperture 32 is provided adjacent the shoulder and communicating with the aperture 29, so that a punch, or the like, driven therethrough, will operate to drive said pin from its seat. The outer flange 20° of each bracket is further provided with a boss 33 through which the aperture 28 extends, said boss having a slot 33a formed in the upper part thereof to communicate with the aperture 28. The oppositely disposed walls of each boss are provided with vertically elongated apertures 33b, and cotter pins 34 are adapted to pass through these apertures and through alining apertures 30a formed in the pins 30. In this manner the pins are prevented from being displaced from their seats. The apertures 33b of the bosses 33 are elongated for convenience in inserting the cotter pins 34 through these apertures and the apertures in the pins 20, which must align therewith. It will be observed that the pins 30 are maintained in position by gravity as well as by the cotter pins 34.

From the foregoing description it will be seen that the brackets 20 may be conveniently attached to the flanges 15d of the dead block by means of the bolts 21 and 22, the bolt 22 of each bracket being passed upwardly through the corresponding pocket 23 before placing the axle member 26 in position in its bearings. The bolts 21 are similarly passed upwardly between the flanges 20° of the brackets, and after the bolts 21 and 22 are in position the extremities thereof are preferably riveted over the coacting nuts. After the brackets have been assembled, the roller 27 may be placed between them and the axle member 26 passed through alining apertures 24 and 25 of the two bracket members. The pins 30 are then placed in position in the alining apertures 28 and 29, and the cotter pins are passed through the alining apertures 33b and 30a to secure the pins in position.

It will be seen that I have provided a strong and rigid structure for supporting the draw-bar of a railway car, and that I have further provided an improved arrangement of parts which may be readily assembled or disassembled for inspection or repair.

Although I have shown and described a particular form of construction, it will be understood that the various parts of the

structure may be formed integrally with each other, or may partake of various different forms and arrangements without departing from the scope of the invention as defined in the appended claims.

70

I claim:

1. In a device of the class described, an end sill, a draw-bar extending through an aperture in said sill, a dead-block secured to said sill around said aperture and having flanges on opposite sides of said draw-bar, a pair of arms secured to said flanges, and a roller supported between said arms to contact with said draw-bar.

2. In a device of the class described, a sill having a part cut away, a draw-bar extending through the aperture formed in said sill, a dead block secured to said sill adjacent said aperture, a pair of detachable arms depending from said dead block on opposite sides of said draw-bar, an axle member detachably mounted in said arms, and a roller journaled on said axle member to support said draw-bar.

3. In a device of the class described, a pair of oppositely disposed brackets, an axle member, said axle member and said brackets having alining apertures therethrough, pins engaging said alining apertures, and a roller journaled on said axle member.

4. In a device of the class described, an end sill of channel form, a dead-block comprising a part seated in the channel of said sill and secured thereto, said block having outwardly directed flanges at the lower part thereof, brackets secured to said flanges and depending therefrom, an axle fixed in said flanges, a roller mounted on said axle, and a draw-bar supported on said roller.

5. In a device of the class described, an end sill having a part thereof cut away, a draw-bar extending through the aperture formed in said sill, a dead-block secured to said sill around said aperture and having flanges extending outwardly from the lower part thereof, a pair of brackets secured to said flanges and extending downwardly therefrom, an axle member mounted in alining apertures in said brackets, pins mounted in an inclined position and engaging inclined apertures in said brackets and said axle member, and a roller mounted on said axle member and supporting said draw-bar.

6. In a device of the class described, a pair of oppositely disposed arms, said arms having alining apertures therethrough, an axle member engaging said apertures, said arms having downwardly inclined pockets formed therein, said axle member having apertures adapted to register with said pockets, and pins engaging said pockets and said apertures in said axle member to secure the latter in position.

7. In a device of the class described, a pair of oppositely disposed arms, said arms

having alining apertures therethrough, an axle member engaging said apertures, said arms having downwardly inclined pockets formed therein, said axle member having 5 apertures adapted to register with said pockets, pins engaging said pockets and said apertures in said axle member to secure the

latter in position, a roller journaled on said axle member, and a draw-bar resting on said roller.

10

In testimony whereof, I have subscribed my name.

EDWARD POSSON.
